(57) **CLAIM**

The ornamental design for a jacket as shown and described.

DESCRIPTION

FIG. 1 is a front, right side perspective view of a jacket showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is an enlarged detail view taken from line 6 in FIG. 4 to illustrate the bottom hem of the jacket with the sleeve removed for ease of illustration;

FIG. 7 is a top plan view thereof; and,

FIG. 8 is a bottom plan view thereof.

In FIGS. 1-8, the shorter wide spaced broken lines on the jacket showing the collar, zipper pulls and inside of the jacket depict features and define portions of the jacket that form no part of the claimed design. The longer, closer spaced broken lines along the bottom of the hem of the jacket depict claimed stitching. The dash-dot-dash broken lines define the bounds of the enlarged detail views in FIGS. 4 and 6 that form no part of the claimed design.
